UNITED STATES PATENT OFFICE.

FREDERICK G. SARGENT, OF GRANITEVILLE, MASSACHUSETTS.

BURRING-MACHINE.

SPECIFICATION forming part of Letters Patent No. 270,988, dated January 23, 1883.

Application filed February 21, 1881. (No model.)

To all whom it may concern:

Be it known that I, F. G. SARGENT, of Graniteville, county of Middlesex, and State of Massachusetts, have invented a new and Improved Burrning-Machine, of which the following is a specification.

My invention relates to machines for picking and opening the wool and separating the burrs and other foreign substances therefrom; and the objects of my improvement are to provide more efficient means for removing the heavier parts of the burrs before they have been long acted upon by the main cylinder of the machine or other working parts, and to provide a convenient cleaning device to prevent the air-draft from becoming choked by the longer fiber which may lodge against the openings into it. I attain these objects by the mechanism illustrated in the accompanying drawings, 20 in which—

Figure 1 is a longitudinal vertical section of my machine. Fig. 2 is a front elevation of a portion thereof. Fig. 3 is an elevation of the clearing attachment.

25 In the drawings, *a'* represents the frame of the machine. *B* is a swinging perpendicular grating; *C*, the endless apron, on which the wool being fed to the machine is placed. This apron delivers it to the feed-rolls *e e*, which 30 feed and hold the fiber while the main or picker cylinder *D* is acting upon it.

E is a horizontal grating placed under the picker-cylinder.

F is a curved perforated metal sheet placed 35 above the picker-cylinder, through which the draft of air caused by the exhaust-fan *G* draws upward the smaller particles of foreign matter loosened by the picker-cylinder.

H is a burring-cylinder placed behind the 40 picker-cylinder, and taking the fiber from it.

I is a guard-cylinder, which knocks off the pieces of burrs while the fiber is held and carried forward by the burr-cylinder.

J is a brush-cylinder, which takes the fiber 45 from the burring-cylinder and discharges it from the machine through the flue *k*.

s is an outwardly-inclined board or plate, placed below the perpendicular grating. This plate terminates in the sharp edge *o* near the 50 picker-cylinder.

A is a brush, whose handle *a* projects through

the frame of the machine. This brush travels on the guide-rods *q q*, which are placed parallel with each other and the perforated plate *F*, and at such a distance that the bristles of the brush will be depressed into the perforations, so as to loosen any accumulated dirt in the openings. This brush is, by means of its handle extending outside the frame on the side, drawn across and pushed back over the perforated plate at any time without stopping the machine or disconnecting any of its parts from their operative position, so that any loosened particles, instead of falling back onto the working parts of the machine, as they would if its 65 exhaust-fan were stopped or its draft injured by opening the apartment *L*, in which the brush works, are carried up by the draft of the exhaust-fan and discharged from the machine.

When grate-bars parallel to the axis of the 70 picker-cylinder are used in the ordinary manner, coming up substantially to the feed-rolls, the larger burrs, which are first loosened by the cylinder striking the wool held by the feed-rolls, are apt to strike such grate-bars and fly 75 back into the fiber carried along by the picker-cylinder, and become incorporated with it, so as to not be easily removed therefrom. At the same time the grate-bars parallel to the axis of the picker-cylinder are more effective to remove heavier particles of dirt, which will easily 80 pass between them, and which are disengaged and drop down somewhat after the burrs first mentioned. To overcome these objections I place the grate-bars *B*, which are parallel to 85 the direction of motion of the picker-cylinder teeth, immediately below the feed-rolls, where they will perform the most efficient service in allowing the burrs to pass through them onto the inclined board *s*, and in placing next below the board *s* the perforated bottom or bars *E*, parallel with the axis of the picker-cylinder. The position of the vertical bars *B* with relation to the board *s* also enables the latter 90 to assist in carrying off the burrs. The perpendicular grating *B* terminates upon the outwardly-inclined guide-board *s* slightly farther from the picking-cylinder *D* than the horizontal grating *E*, so that any burr falling against one of the perpendicular bars, not having sufficient velocity or force to be deflected side- 95 wise and pass through between the bars, will, 100

by sliding down it, come in contact with the board *s*, and, if it has sufficient weight to resist the air-current at all, will either slide out at once upon the board or remain until some current of air or heavier falling particles of dirt disturb its balance against the bar, when it will slide out of the machine. The perpendicular grating, unlike the horizontal, does not present one bar above another in the way of the falling burrs, and the openings between the bars are not each narrowed by the width of the preceding bar on the line of a falling body. The perpendicular grating *B* is made adjustable by being hung upon a rock-shaft, *b*, and it can be swung outward and downward by the attendant, so as to permit any accumulating substances to fall out, or to permit of its being cleaned by hand without endangering the operator or stopping the machine.

20 The arrows seen in the drawings indicate the direction of motion of the moving parts or air-currents as appears from their position.

What I claim is—

1. The combination, with the feed-rolls *ee* and picker-cylinder *D*, of the perpendicular grating *B*, placed below the feed-rolls, board *s*, and horizontal grating or perforated sheet *E*, substantially as described. 25

2. The combination of the feed-rolls *ee* and picker-cylinder *D* with the perpendicular grating *B* and outwardly-inclined guide-board *s*, having the interprojecting edge *o*, and the cylinder-case beneath the board, substantially as described. 30

3. The combination of the picker-cylinder *D*, 35 exhaust-fan *G*, and perforated plate *F* with the brush *A*, inclosed in the air-draft chamber, and suitable mechanism for operating the same, substantially as described.

FREDERICK G. SARGENT.
